LAMP BASE

Edith Norton, Los Angeles, Calif.

Application April 16, 1949, Serial No. 2,072

Term of patent 14 years

(Cl. D48—20)

To all whom it may concern:

Be it known that I, Edith Norton, a citizen of the United States, residing in Los Angeles, in the county of Los Angeles, State of California, have invented a new, original, and ornamental Design for a Lamp Base, of which the following is a specification, reference being had to the accompanying drawings forming a part thereof;

The characteristic features of my new design reside in those portions shown by means of full lines in the drawing.

I claim:

The ornamental design for a lamp base, substantially as shown and described.

EDITH NORTON.
